Inventor:

Charles D. Reeve,

By Dryerforth, Lee, Clinton and Niles,
Atteys.

UNITED STATES PATENT OFFICE.

CHARLES D. REEVE, OF GRAND RAPIDS, MICHIGAN, ASSIGNOR TO WILCOX PRESSED STEEL COMPANY, OF CHICAGO, ILLINOIS, A CORPORATION OF ILLINOIS.

HASP.

1,401,491.

Specification of Letters Patent. Patented Dec. 27, 1921.

Application filed December 20, 1920. Serial No. 431,976.

To all whom it may concern:

Be it known that I, CHARLES D. REEVE, a citizen of the United States, residing at Grand Rapids, in the county of Kent and

5 State of Michigan, have invented a new and useful Improvement in Hasps, of which the following is a specification.

My invention relates more particularly to hasps of the type employing a plate-section 10 adapted to be secured to one of the parts of a structure, the parts of which are to be connected together, and having a tongue portion pivotally supported thereon and adapted to engage with a lock device provided on the 15 other part of the structure; this type of lock being such as is commonly employed for suit cases and usually involving a spring which tends to normally force the tongue out of engagement with the lock.

20 My primary object is to provide a novel, simple and inexpensive construction of hasp of the general character above stated, the parts of which may be readily assembled. A further object is to so construct the hasp 25 that the prying apart of the sections thereof, when the hasp engages the lock, is rendered very difficult as compared with prior structures of substantially the same simplicity and cost of manufacture.

30 Referring to the accompanying drawings:—

Figure 1 is a view in front elevation of a hasp constructed in accordance with my invention. Fig. 2 is a rear view of the same. 35 Fig. 3 is a rear view of the plate portion of the hasp. Fig. 4 is a rear view of the tongue portion of the hasp. Fig. 5 is a section taken at the line 5 on Fig. 3 and viewed in the direction of the arrow. Fig. 6 is an edge view 40 of the tongue of Fig. 4. Fig. 7 is a section taken at the line 7 on Fig. 2 and viewed in the direction of the arrow; and Fig. 8, a view like Fig. 2 of a modification of the structure shown in the preceding figures.

45 Referring more particularly to Figs. 1 to 7 inclusive, the hasp is shown as constructed of a plate portion 9 shown as of general elliptical form and containing openings 10 therethrough at which it is adapted to be 50 secured to one of the parts to be locked together, as for example the cover of a suitcase, as is the usual practice in this general character of locking means. The plate portion is formed with a recess 11 in one of its edges so shaped as to present a lug 12 of less

width than the width of the recess, with slots 13 in the body of the plate 9 beyond the lug 12. The metal of the plate 9 at opposite sides of the recess 11 is deflected forwardly to present the surfaces 14 which preferably 60 extend in front of the plane occupied by the front surface of the main portion of the plate 9, as clearly represented in Fig. 5. The marginal edge of the plate 9 is preferably 65 rearwardly bent at right angles to the face of the plate to present the flange 15 at which the plate bears against the structure to which it is attached in use, this flange also serving to strengthen the plate.

The tongue portion of the hasp is represented at 16, the body portion thereof being 70 preferably provided about its marginal edge with rearwardly-extending flanges 17 and 18, the said body portion containing an opening 19 near one end in which a stud 75 20 slotted at 21 is secured for engagement with a lock device (not shown) as in accordance with common practice. The tongue 16 is provided at its upper end portion, with lugs 22 which extend through the slots 13 80 and are shown as turned upwardly and toward the inner face of the plate 9 to interlock these parts together, but permit the tongue to be swung on the plate 9, the tongue also carrying at opposite sides at its 85 flange 17, outwardly-extending lugs 23 which, as shown in Fig. 2, extend into overlapping position relative to the surfaces 14 of the plate 9 and serve to limit outward swinging movement of the tongue on the 90 plate under the action of a leaf spring 24 connected at its lower end with the tongue, as through the medium of the stud 20 as shown, and bearing, under its spring action, against the front face of the lug 12 which it 95 flatwise opposes, the arrangement of the parts just described being such that the spring operates to normally swing the tongue 16 on the plate 9 to the position represented in Fig. 7.

100 In the constructing of the hasp, the lugs 22 are preferably provided as extending at right angles to the body portion of the tongue 16 as shown in Figs. 4 to 6, and in assembling the tongue with the plate, the 105 tongue may be introduced at its lug-equipped end into the recess 11 from the rear side of the plate, the tongue extending substantially at right angles to the plate, to a position in which the lugs 23 underlap 110

the surfaces 14, whereupon the one assembling the parts swings the tongue 16 in a direction to cause the lugs 22 to enter the slots 13 from the front side of the plate, 5 these lugs thereupon being bent over as shown in Fig. 2, or upset to interlock them with the plate 9, but affording the desired swinging movement of the tongue on the plate. The spring 24 and stud 20 may then be 10 applied to the position shown, or, if desired, the spring and stud may be secured to the tongue before it is assembled with the plate 9.

While it is desirable that two of the lugs 15 22 be employed, extending through two slots 13, this is not necessary so far as my invention is concerned, it being within my invention to provide a greater or less number of the lugs and slots, and where a single lug 20 extending through a slot in the plate is provided, it is preferably provided midway between the edges of the tongue such as shown of the lug 25 in Fig. 8 wherein it extends through a slot in the plate 9 and represented 25 at 26, the structure shown in this figure otherwise being the same as that shown in the preceding figures.

It will be understood from the foregoing that by constructing the hasp as shown and 30 described, the plate-portion 9 may be formed of a single section and still the parts of the hasp structure be rendered very durable and highly resistant to disassembly by persons attempting to pry the tongue from 35 the plate. Furthermore the device is very simple and may be readily and economically manufactured and the parts be quickly assembled.

While I have illustrated and described 40 certain particular constructions embodying my invention, I do not wish to be understood as intending to limit it thereto as the same may be variously modified and altered and the invention be embodied in 45 other forms, without departing from the spirit of my invention.

What I claim as new, and desire to secure by Letters Patent, is:

1. A hasp formed of a single plate structure and a tongue portion, said plate being apertured and said tongue having a lug-equipped portion which extends through said apertured portion, the portions of the walls of said apertured portion which extend crosswise of the length of the tongue opposing opposite surfaces of said lug-equipped portion and forming an interlock between said tongue and plate adapting said tongue to be swung on said plate.
2. A hasp formed of a single plate structure and a tongue portion, said plate being apertured and said tongue having a lug-equipped portion which extends through said apertured portion, the portions of the 65 walls of said apertured portion which ex-

tend crosswise of the length of the tongue opposing opposite surfaces of said lug-equipped portion and forming an interlock between said tongue and plate adapting said tongue to be swung on said plate, and projections on said tongue extending into overlapping relation with said plate for limiting the swinging of said tongue outwardly on said plate.

3. A hasp formed of a plate portion and 75 a tongue portion, said plate portion being formed of a single piece of metal containing a recess in an edge thereof, with the side walls of the recess deflected forwardly, with a lug extending outwardly into said recess, 80 said plate having a slotted portion beyond said lug, said tongue having a lug-equipped portion at which it extends through said slotted portion, the portions of the walls of said slotted portion which extend crosswise 85 of the length of the tongue opposing opposite surfaces of said lug-equipped portion and forming an interlock between said tongue and plate adapting said tongue to be swung on said plate, said tongue having 90 laterally-extending projections which extend into overlapping relation with said plate at the rear side thereof, and a spring operatively engaging at one end with said tongue and at its opposite end engaging said 95 lug for the purpose set forth.

4. A hasp formed of a single plate structure and a tongue portion, said plate being apertured and said tongue having a lug-equipped portion which extends through 100 said apertured portion, the portions of the walls of said apertured portion which extend crosswise of the length of the tongue opposing opposite surfaces of said lug-equipped portion and forming an interlock 105 between said tongue and plate adapting said tongue to be swung on said plate, and means for limiting the swinging of said tongue on said plate.

5. A hasp formed of a single plate structure, a tongue portion supported, and held, on said plate by interengaging parts of said plate and tongue to have swinging movement on said plate, and a spring for said tongue engaging at one end with said tongue 110 and at its opposite end with said plate.

6. A hasp formed of a plate portion and a tongue portion, said plate portion being formed of a single piece of metal containing a recess in an edge thereof, with the side walls of the recess deflected forwardly, 120 said plate having a slotted portion beyond said recess, said tongue having a lug-equipped portion at which it extends through said slotted portion, the portions of the walls of said slotted portion which extend crosswise of the length of the tongue opposing opposite surfaces of said lug-equipped portion and forming an interlock 125 between said tongue and plate adapting said 130

tongue to be swung on said plate, said tongue having laterally-extending projections which extend into overlapped relation with said plate at the rear side thereof, and a spring 5 operatively engaging at one end with said plate below said slotted portion and at its opposite end engaging said lug, for the purpose set forth.

7. A hasp formed of a single plate portion and a tongue portion, said plate being apertured and said tongue having a lug-equipped portion which extends through said apertured portion, said lug having a rearwardly-extending part which lies within 10 said aperture, with the upper and lower walls of the latter opposing said rearwardly-extending part, and said lug having a part which extends at an angle to the rearwardly-extending part thereof and opposes the rear 15

face of said plate, the parts being so constructed and arranged as to permit said tongue to swing on said plate.

8. A hasp formed of a single plate portion, a tongue portion, said plate being apertured and said tongue having a lug-equipped portion which extends through said apertured portion, said lug having a rearwardly-extending part which lies within said aperture, with the upper and lower walls of the latter opposing said rearwardly-extending part, and said lug having a part which extends at an angle to the rearwardly-extending part thereof and opposes the rear face of said plate, the parts being so constructed 20 and arranged as to permit said tongue to swing on said plate, and means for limiting the swinging of said tongue on said plate.

CHARLES D. REEVE.
